(57) **CLAIM**

The ornamental design for an optical element for optical communication, as shown and described herein.

DESCRIPTION

FIG. 1 is a perspective view of an optical element for optical communication showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

Oblique lines show a transparent, reflective, or shiny surface, and not surface ornamentation. Elements visible behind transparent surfaces are shown in light, full lines.
